(57) **CLAIM**

The ornamental design for a ceiling light, as shown and described herein.

DESCRIPTION

FIG. 1 is a perspective view of a ceiling light, showing our new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a perspective view of a ceiling light at a different angle;

FIG. 9 is a perspective view from a bottom-right side thereof;

FIG. 10 is a perspective view from a bottom-left side thereof;

FIG. 11 is an enlarged left side view thereof;

FIG. 12 is an enlarged right side view thereof;

FIG. 13 is a partial enlargement view of portion 13 shown in FIG. 1;

FIG. 14 is a partial enlargement view of portion 14 shown in FIG. 8;

FIG. 15 is a partial enlargement view of portion 15 shown in FIG. 9; and,

FIG. 16 is a partial enlargement view of portion 16 shown in FIG. 10.

The broken lines illustrate portions of the ceiling light that form no part of the claimed design.

1 Claim, 13 Drawing Sheets
